(57) **CLAIM**

The ornamental design for container with shrimp and sauce cups, as shown and described.

DESCRIPTION

FIG. 1 is a top isometric view of a container with shrimp and sauce cups.

FIG. 2 is a top view thereof.

FIG. 3 is a front view thereof.

FIG. 4 is a rear view thereof.

FIG. 5 is a left view thereof.

FIG. 6 is a right view thereof; and,

FIG. 7 is a bottom view thereof.

The broken lines shown illustrate portions of the container with shrimp and sauce cups that form no part of the claimed design.

1 Claim, 5 Drawing Sheets
